UNITED STATES PATENT OFFICE

137,881

DESIGN FOR A SAUCER

Thomas W. Wall, New Rochelle, N. Y.

Application October 2, 1943, Serial No. 111,258

Term of patent 14 years

(Cl. D44—9)

To all whom it may concern:

Be it known that I, Thomas W. Wall, a citizen of the United States, residing at New Rochelle, in the county of Westchester and State of New York, have invented a new, original, and ornamental Design for Saucers, of which the following is a specification, reference being had to the accompanying drawing, forming a part thereof.

Figure 1 is a top plan view of a saucer, showing my new design;

Figure 2 is a bottom plan view;
Figure 3 is a side elevational view thereof; and
Figure 4 is a diametrical sectional view through the saucer, taken along the line 4—4 of Figure 1, and in the direction of the arrows.

I claim:

The ornamental design for a saucer, as shown.

THOMAS W. WALL.
